UNITED STATES PATENT OFFICE.

ARTHUR S. HUCKINS, OF PHILADELPHIA, PENNSYLVANIA.

ELECTRIC SIGNALING DEVICE.

1,120,499.

Specification of Letters Patent.

Patented Dec. 8, 1914.

Application filed January 14, 1914. Serial No. 812,079.

To all whom it may concern:

Be it known that I, ARTHUR S. HUCKINS, a citizen of the United States, residing in Philadelphia, Pennsylvania, have invented 5 certain Improvements in Electric Signaling Devices, of which the following is a specification.

The object of my invention is to so construct an electric signaling apparatus, such 10 for instance as a door bell, that the same will automatically indicate when it is inoperative because of the weakening of, or interference with, the electric current upon which it depends for its proper operation. This object 15 I attain in the manner hereinafter set forth, reference being had to the accompanying drawing, in which—

Figure 1 is a vertical sectional view of the door plate and push button of an electrical 20 signaling device constructed in accordance with my invention, this view also showing parts of the line wires and the conventional representation of a battery for supplying current to the line; Fig. 2 is a similar view 25 illustrating a slight modification of my invention, and Fig. 3 is a like view of part of the apparatus, illustrating another modification.

In the drawing, I have illustrated my invention as applied to an ordinary type of 30 electric door bell, 1 representing the door plate or casing and 2 the casing applied thereto for the reception of the push button 3 and the spring terminal contacts 4 and 5, 35 respectively, for the positive and negative terminals *x* and *y* of the battery or other electric generator *m*, all of these parts being as usual, except that the electric circuit includes an electromagnet 6, which, in the 40 present instance is mounted on the inside of the casing 1 by means of a bracket 7. Also mounted on the inside of the casing 1 is a spring arm 8 whose upper end is bent inwardly as shown at 8^a to serve as a support 45 for a flap 9 pivotally mounted on the inside of the casing 1, and having on its face an inscription such as "Bell out of order" "Please knock" or the like. When this flap is retained in elevated position, as 50 shown in Fig. 1, it is invisible but when it is permitted to drop, it will expose its inscription through an opening 10 in the casing 1, this opening having a cover 11 of glass, celluloid, or other transparent material. The spring plate 8 has a projecting 55 knob 12 which contacts with the spring ter-

95
minal 5 so that, when said terminal is pushed inward, by contact of the terminal 4 therewith on the depression of the push button 3, the upper bent end of the spring arm 8 60 will be freed from engagement with the flap 9 and in the absence of some other support said flap will fall. Before the depression of the spring arm 8, however, the terminals 4 and 5 were brought into contact with one 65 another and the circuit was completed through the bell magnet and also through the magnet 6. The flap 9 acts as an armature for said magnet 6 and as long as the latter remains energized said armature will 70 be attracted to the pole of the magnet and prevented from dropping. Before the current through the bell magnet and magnet 6 is discontinued by release of pressure upon the push button 3 the terminals 4 and 5 75 have moved outwardly sufficient to remove the pressure of the terminal 5 from the knob 12 of the spring arm 8 and the bent upper end 8^a of the latter has resumed its supporting position in respect to the flap 9, hence 80 the latter will not drop when the current through the magnet 6 is interrupted and it ceases to exert magnetic attraction upon the flap 9. If, however, the electric current is so weakened as not to properly energize 85 the bell magnet and cause the ring of the bell it will also fail to energize the magnet 6 sufficiently to cause it to properly attract the flap, consequently the latter will drop as soon as the support of the arm 8 is re- 90 moved therefrom and thus indicate to the person who is pressing the button 3 that the bell is out of order and that some other means of signaling the occupants of the 95 house will have to be resorted to.

In the operation of the ordinary electric door bell the circuit is automatically interrupted at frequent intervals in order to effect vibration of the arm carrying the bell hammer and such intermittent interrupting 100 of the circuit through the magnet 6 will also be effected, but the circuit is not broken long enough to permit the armature to escape from the influence of the magnet, hence the flap 9 will not fall, and before the circuit through the magnet 6 is permanently broken by the release of the push button 3 the spring arm 8 will be in position to engage the flap 9 and prevent the same from 105 dropping.

While I prefer to cause the magnet 6 to act directly upon the flap 9 as an armature,

this is not necessary to the proper carrying out of my invention as said magnet may, if desired, act through the medium of an intervening retainer such for instance as the pivoted trigger shown at 13 in Fig. 2, this trigger being hooked and alternating with the spring arm 8 as a means for supporting the flap 9 in the elevated position, the magnet 6 being energized and the trigger moved into locking position thereby before the flap 9 is deprived of the support of the finger 8. When such a supporting trigger is used, however, the interruption of the circuit through the magnet 6 at the same time that the circuit is interrupted through the bell magnet might cause failure in the proper operation of the supporting trigger, hence in this case I prefer to place the magnet 6 in a branch circuit *n* upon which the circuit breaker of the bell has no influence, the circuit through the magnet 6 being maintained as long as the terminals 4 and 5 are in contact with one another. I may also use a sliding indicator 9^a, as shown in Fig. 3 instead of a swinging indicator such as shown in Figs. 1 and 2. In this case the armature 14 when attracted by the magnet is drawn into line with a lug 15 on the back of the supporting arm 8 and prevents the latter from being pushed inwardly far enough to remove its support from the indicator 9^a, but if the armature 14 is not attracted it remains below the lug 15 and permits such inward movement of the arm 8 as to release the indicator and permit it to drop.

I claim:—

1. The combination of an electromagnetic signal circuit, a controller therefor, an electromagnet which receives current from the same source as the signal circuit and is controlled by the same means, an indicator, a

retainer therefor, operated by the controller, to release the indicator, and means whereby the magnet, when energized, prevents such release. 45

2. The combination of an electromagnetic signal circuit, a controller therefor, an electromagnet which receives current from the same source as the signal circuit and is controlled by the same means, an indicator, means whereby the same is retained in inoperative position by said magnet when the latter is energized, and another indicator retainer operated by the controller to release said indicator. 50 55

3. The combination of an electromagnetic signal circuit, a controller therefor, a magnet which receives current from the same source as the signal circuit and is controlled by the same means, an indicator constituting an armature for said magnet, and a retainer for said indicator operated by the controller to release the indicator. 60

4. The combination of the circuit closing contacts of an electromagnetic signaling device, a push button for closing said contacts, a magnet energized from the same source as the signal circuit, an indicator, means whereby the same is supported by said magnet when the latter is energized, an arm serving to support said indicator independently of the magnet, and means whereby said arm is removed from its supporting position when the circuit is closed. 65 70

In testimony whereof, I have signed my name to this specification, in the presence of two subscribing witnesses. 75

ARTHUR S. HUCKINS.
